PRODUCTION OF N-(HYDROXY-ARYL)
ASPARTIC ACID DIESTERS

9 Claims. (Cl. 260—471)

1

This invention relates to the production of compounds of the class of N-(hydroxy-aryl) aspartic acid diesters that are particularly advantageous for use as antioxidants in hydrocarbon oils, for example, as gum inhibitors for gasoline.

A gum inhibitor for use in fuels for internal combustion motors must possess a combination of several properties. It must be effective for inhibiting gum formation at such small concentration that the quantity of inhibitor added to the fuel does not alter the performance of the fuel. It must be sufficiently volatile to avoid the formation of deposits in the carburetting system. It must be sufficiently stable to retain its effectiveness upon storage of the fuel, and sufficiently inert and insoluble in water to avoid substantial destruction or removal of the inhibitor upon contact of the fuel with containers and with water as the fuel is stored and handled. Furthermore, a satisfactory gum inhibitor must be soluble in the fuel to be stabilized in the small concentrations at which it is used for inhibiting gum formation and must not alter the appearance of the fuel in such a way as to make the stabilized fuel commercially unacceptable; gasoline or other clear distillate which is made turbid and dark colored upon addition of a stabilizer, for example, is not generally acceptable in commerce.

As pointed out in Liston Patent 2,207,063 of July 9, 1940, the N-(hydroxy-aryl) and N-(aminaryl) aspartic acid diesters have particular merit as gum inhibitors for fuels for internal combustion motors. These compounds give satisfactory stabilization in relatively low concentrations, do not form deposits in carburetting systems, are not only stable upon storage and handling of the fuel, but are even improved in effectiveness with such storage and handling in the presence of water. It has been found, however, that the N-(hydroxy-aryl) aspartic acid diester inhibitors made as described in this patent have the disadvantage of imparting a pronounced cloudiness to the fuels in which they are used. Such cloudiness does not interfere with the effectiveness of the compounds in preventing gum formation but does make the compounds unacceptable in commerce.

We have now discovered a new method of preparing N-(hydroxy-aryl) aspartic acid diester antioxidants which, when added to a motor fuel such as gasoline in sufficient concentration for inhibiting gum formation, impart no haze or cloudiness to the fuel. Our new method of preparing these compounds involves condensing a diester of maleic or fumaric acid with a hydroxy-

2

aryl amine in the presence of a monohydric alcohol having an appreciable water solubility, i. e. soluble in water to the extent of at least 0.5% and preferably at least about 5% by weight at room temperature (25° C.). Water is also preferably present in the condensation reaction mixture and the condensation is preferably carried out in the presence of a small amount of an alkaline material. The reaction should be carried out at a temperature below 150° C., preferably below 100° C., and most advantageously in the range 60° to 90° C.

One possible explanation which may be advanced for the fact that the process of this invention produces an N-(hydroxy-aryl) aspartic acid diester which, when added to motor fuel such as gasoline, gives clear solutions, whereas such diesters made in the absence of a diluent alcohol give highly turbid solutions, is that the process of this invention results in the production of a product substantially free, or containing a substantially smaller amount, of constituents such as para-aminophenols, amides and acids, which are believed to impart haze and turbidity to the motor fuel. Another factor is believed to be an alcoholysis reaction that takes place at the same time as the condensation, whereby radicals from the diluent alcohol are substituted to some extent for the radicals of the diester employed in the condensation reaction, forming a complex mixture of aspartic acid diesters. Thus, when condensing diisobutyl maleate and para-aminophenol in the presence of ethyl alcohol, it has been found that ethyl groups are substituted for the isobutyl groups in the final aspartic acid diester to the extent of about 15%, probably forming minor amounts of both a diethyl aspartate and an ethylisobutyl aspartate, in addition to the predominant diisobutyl aspartate.

The composition that is produced when the diluent alcohol contains different radicals than those present in the maleic or fumaric diester, we have found, is a particularly advantageous gum inhibitor. This new composition is a mixture of two or more diesters of the above-described N-substituted aspartic acid, in which, on the average, radicals derived from the diluent alcohol make up from about 5 to 50 mol % of the alcohol radicals in the N-substituted aspartic diesters.

In a preferred method of preparing N-(hydroxy-aryl) aspartic acid diesters in accordance with the process of our invention, the reactants are mixed and the mixture is heated under reflux at the temperature indicated, at atmospheric pres-

sure, or, if desired, at higher or lower pressures, until the reaction is substantially complete or reaches a point when substantially no further reaction takes place. This may require from 2 to 120 hours depending on the temperature. Completion of the reaction is determined by analyzing a sample of the reaction mixture for unreacted aminophenol.

The diester of maleic or fumaric acid employed in the reaction may be any mixed or symmetric diester, but it is preferably one in which the alcohol radicals are alkoxy or aralkoxy; i. e. the diester reactant is preferably a dialkyl (including dicycloalkyl) or a diaralkyl maleate or fumarate, the two alcohol radicals being either the same or dissimilar. Examples of suitable esters include: dimethyl, diethyl, diisopropyl, diisobutyl, di-secondary butyl, di-(2'-ethyl-hexyl), dilauryl, dibenzyl, dicyclohexyl, di-tetrahydrofurfuryl, cetyl isobutyl, ethyl isobutyl, methyl ethyl and ethyl isopropyl maleate or fumarate. Such diesters may conveniently be prepared just prior to carrying out the condensation reaction of the invention by refluxing maleic anhydride or maleic or fumaric acid with the desired alcohol or alcohols for esterifying the acid or anhydride. A dialkylmaleate or fumarate in which each alkyl group contains no more than 5 carbon atoms is particularly suitable.

The hydroxy-aryl amine condensed with the maleic or fumaric ester may be a hydroxy-amino derivative of benzene, naphthalene, diphenyl, or the like, but is preferably a mononuclear aminophenol. This amine reactant is preferably employed in about equimolecular proportion to the fumaric or maleic ester, but either of the reactants may be employed in excess. By carrying out the condensation in accordance with our new process, there is substantially less danger of amidation of the ester even when an excess of the amine reactant is present than is the case when the reaction is carried out in the absence of the diluent alcohol. Suitable hydroxy-aryl amines for use in preparing our new compounds include: para-aminophenol, ortho-aminophenol, 2,4-diaminophenol, amino catechol, amino hydroquinone, 3-amino-4-hydroxy toluene, 1-amino-5-hydroxy naphthalene, 2-hydroxy-5-aminodiphenyl, and the like.

The alcohols which are present in carrying out the condensation in accordance with our new process as above stated are the monohydric alcohols having appreciable water solubility, i. e. soluble in water to the extent of at least 0.5% and preferably at least about 5% by weight. These include: methyl alcohol, ethyl alcohol, propyl alcohol, isopropyl alcohol, the various butyl alcohols, the amyl alcohols (e. g. normal amyl alcohol, methyl-n-propyl carbinol, etc.), Cellosolve (beta-ethoxy ethyl alcohol), Methyl Cellosolve (beta-methoxy ethyl alcohol), Butyl Cellosolve, Carbitol (monoethyl ether of diethylene glycol). These alcohols may be employed in the condensation reaction mixture with or without water but are preferably used with water; i. e. the diluent for the condensation reaction may range from a substantially anhydrous alcohol to a dilute aqueous alcohol solution containing, for example, as little as about 5% alcohol, and the alcohol present will still exert its ameliorating effect on the reaction. Preferably, an aqueous alcohol diluent should contain not less than 25% by weight of alcohol. The alcohol (or aqueous alcohol solution) should make up at least 15% by weight of the condensation reaction mixture and may be present to the extent of 70% of the reaction mix-

ture. Preferably, the anhydrous or aqueous alcohol is present to the extent of from one-half to five times the weight of maleic or fumaric diester reactant. Our preferred alcohol diluent is an aqueous solution of an alcohol of not more than 5 carbon atoms, advantageously ethyl alcohol, most advantageously a solution of about 40% to 60% concentration. This ethyl alcohol solution most advantageously makes up from about 40% to 60% of the condensation reaction mixture.

The alkalies suitable for addition to the condensation reaction mixture of our invention include particularly the tertiary nitrogen bases and organic ammonium compounds which are inert towards the reactants, e. g. pyridine, quinoline, dimethylaniline and triethylamine, and inorganic alkaline salts such as sodium carbonate and bicarbonate, trisodium phosphate. Such alkaline materials are preferably added in amount from 0.4% to 4% of the weight of the maleic or fumaric diester; i. e. preferably make up from 0.1% to 1% of the condensation reaction mixture.

The products of the present invention may be employed as gum inhibitors for motor fuels derived from cracked hydrocarbon distillates in general and particularly for internal combustion motor fuels such as gasolines that contain appreciable amounts of unsaturated compounds that tend to polymerize to gums. For accomplishing its inhibiting action, the compound of our invention is added to the motor fuel in only a small amount, preferably to yield a concentration between 0.001% and 0.1% by weight of the mixture. The solid compounds may be added directly to the gasoline or may first be dissolved or suspended in a diluent miscible with the gasoline, for example, in anhydrous ethyl alcohol, butyl alcohol or propyl alcohol or any other suitable alcohol. We have found it is quite advantageous either to add the solid inhibitor directly to gasoline or to dissolve it first in ethyl alcohol and add this solution to the gasoline.

As above pointed out, inhibitor compounds prepared in accordance with our invention have the important advantage of not appreciably altering the appearance of the gasoline; i. e. although some gasolines stabilized by compounds prepared in accordance with our invention may show a faint haze in a cone of strong light directed through the gasoline, they do not show the undesirable haze or opacity visible to the naked eye under normal lighting conditions that results from using as gum inhibitors compounds of the same class prepared by carrying out the condensation in the absence of an alcohol diluent as above described.

The following examples are illustrative of our invention. All parts are by weight.

Example 1.—A mixture of 98 parts of maleic anhydride, 156 parts of isobutyl alcohol, 17.3 parts of toluene and 0.25 part of p-toluene-sulfonic acid was heated to boiling in glass apparatus and refluxed until esterification was complete, as indicated when no further water was distilled from the mass. The reaction mixture was cooled to about room temperature after which 158 parts of 2B ethyl alcohol (96% alcohol denatured with 1/2 gallon of benzene per 100 gallons of ethyl alcohol in accordance with the specifications for 2B ethyl alcohol: U. S. Treasury Dept., Bur. of Internal Rev., Appendix to Regns. #3. Formulae for completely and specially denatured alcohols, 1942, page 14), 200 parts of water, 1 part 75 of pyridine and 109 parts of p-aminophenol were

added. The mixture thus obtained was refluxed (temperature 84°-86° C.) with agitation on a steam bath for 72 hours, after which it was cooled to 50° C. and sludge filtered to remove insoluble particles. The filtrate was mixed with a solution of 200 parts by volume of 2B ethyl alcohol and 200 parts by volume of water, and the resulting agitated emulsion was cooled to room temperature and stirred until the emulsion was broken and fine particles of tan crystals were formed. The mass was agitated for about 1/2 hour to complete the crystallization of the solid, which was washed with a solution of 100 parts by volume of 2B ethyl alcohol and 100 parts by volume of water, then with about 6000 parts of water, and dried at 40°-50° C. in vacuo to yield a finely-divided light tan solid. The product was a mixture of ethyl and isobutyl esters of N-(p-hydroxy-phenyl) aspartic acid, probably a mixture of N-(p-hydroxy-phenyl) diethyl aspartate, N-(p-hydroxy-phenyl) diisobutyl aspartate and N-(p-hydroxy-phenyl) monoethyl monoisobutyl aspartate in unknown proportions. On the average, ethyl radicals constituted about 15 mol per cent of the ester-forming radicals and isobutyl radicals about 85 mol per cent (the mol per cent referring to mols of corresponding alcohol). The melting point of the product over a number of runs varied slightly between the temperatures of 65° and 80° C. The product was appreciably lighter in color than the product resulting from the practice of a process which differs from that of this example in that no diluent alcohol was used. The yield ranged from about 70% to 80% of theory calculated as N-(p-hydroxy-phenyl) diisobutyl aspartate.

In two parallel tests, the product thus obtained and a product prepared by a process which differs from Example 1, above, chiefly in that no diluent alcohol was used, which latter product is hereafter referred to as Prior Product, were each added to separate samples of the same gasoline. This was accomplished by dissolving 1.35 grams of each gum inhibitor in sufficient anhydrous 2B ethyl alcohol to give a volume of 10 cc's, and adding 0.01 cc. of each solution to 50 cc. of Skellysolve C (a water-white low-boiling hydrocarbon material consisting essentially of paraffinic hydrocarbons).

The solution of Skellysolve C, prepared as described above from the product obtained as described by the process of our invention, was completely clear to the naked eye at ordinary temperatures and under normal lighting conditions and showed only a slight Tyndall effect when illuminated by a cone of light. The Skellysolve C solution of the Prior Product appeared considerably turbid under normal lighting conditions. Both the present product and the Prior Product possessed the same efficiency when tested as gasoline gum inhibitors.

Example 2.—This example illustrates the use of aqueous ethyl alcohol of 90%, 70% and 30% volume concentration as diluent.

114 parts of diisobutyl maleate, 54.5 parts of para-aminophenol, and about 155 parts of the 2B ethyl alcohol, 10 parts of water, and 0.5 part pyridine were charged to a still equipped with an agitator and a reflux condenser. The mixture was agitated and refluxed for 72 hours, thus bringing about the desired condensation in the presence of about 90 volume per cent aqueous ethyl alcohol. The reaction mixture was allowed to cool somewhat and a solution of an additional

190 parts of water and 8 parts of the 2B ethyl alcohol were added. This dilution gave approximately 400 parts of a 50% by volume aqueous alcohol from which to isolate the product. The mixture was filtered and the filtrate was agitated rapidly and cooled. A solid separated in rather large pellets. This product was filtered off and washed with about 200 parts of the 50% aqueous ethyl alcohol. The solid was then re-slurried in 500 parts of water, filtered and washed with 2500 parts of water. The product was dried at 40°-50° C. in a vacuum oven. 142 parts of product were thus obtained.

This procedure was repeated, in one case carrying out the condensation in the presence of an aqueous alcohol solution containing about 70% by volume of alcohol and in another case in the presence of an aqueous alcohol solution containing about 30% by volume ethyl alcohol. Reaction in these solvents gave 150 parts and 132 parts of product, respectively.

Each of these three products, when added to gasoline, as described in Example 1, gave substantially less haze than the Prior Product.

Example 3.—Isopropyl alcohol was substituted for the ethyl alcohol in our preferred method of preparation, as described in Examples 1 and 2, above:

114 parts of diisobutyl maleate, 54.5 parts of para-aminophenol, about 80 parts of isopropyl alcohol, 100 parts of water, and 0.5 part of pyridine were refluxed for 72 hours. The reaction mixture was allowed to cool slightly and was then filtered. The filtrate was diluted with 200 parts of approximately 50% aqueous ethyl alcohol, agitated and cooled. The light yellow solid which separated was filtered off and washed with 200 parts of approximately 50% aqueous ethyl alcohol and 2500 parts of water and was then dried in a vacuum oven at 50°-60° C. The resulting product obtained in a yield of 124 parts was employed as a gum inhibitor for gasoline as above described and the gasoline showed substantially less haze when a conical beam of light was directed therethrough than the Prior Product.

Example 4.—This example illustrates the use of anhydrous methyl alcohol as diluent.

57 parts of diisobutyl maleate and 27.2 parts of para-aminophenol were refluxed in about 160 parts of methyl alcohol for 96 hours. The reaction mixture was filtered and the filtrate was drowned in 2000 parts of cold water. The solid which formed was filtered off and dried in a vacuum oven at room temperature. This product, when added to gasoline, gave substantially less haze than the Prior Product.

Example 5.—This example illustrates the use of a mixture of Cellosolve, ethyl alcohol and water as diluent.

About 57 parts of diisobutyl maleate, 27.2 parts of para-aminophenol, 100 parts of Cellosolve, 102 parts of 2B ethyl alcohol and 69 parts of water were mixed, warmed slightly and agitated until 65 a homogeneous solution was obtained. The solution was stoppered and allowed to stand at room temperature for about 69 days. At the end of that time, the mixture was chilled and the insoluble material was removed by filtration. The filtrate was drowned in 1500 parts of water. A light tan solid was isolated, washed with about 200 parts of a volatile paraffinic hydrocarbon solvent and dried at room temperature in a vacuum oven. The product gave substantially no haze when incorporated in gasoline as a gum inhibitor.

Various N-(hydroxyl-aryl) aspartic acid diesters may each be prepared by procedures such as those described in the above examples, by employing in each case a diluent alcohol containing the same radicals as the diester, and although the chemical composition of the compound obtained will apparently be substantially the same as the compounds of said Patent 2,207,064, nevertheless a gasoline containing the ester prepared in accordance with our invention in the concentration proper for inhibiting gum formation, is substantially clear under normal lighting conditions, whereas the compound, nominally the same, prepared without the diluent alcohol gives an undesirable cloudy gasoline. The compounds listed below are typical gum inhibitors that may be thus prepared by the process of our invention:

N-(p-hydroxy-phenyl) diethyl aspartate
 N-(p-hydroxy-phenyl) diisopropyl aspartate
 N-(p-hydroxy-phenyl) di-secondary butyl aspartate
 N-(p-hydroxy-phenyl) di-(2'-ethyl-hexyl) aspartate
 N-(p-hydroxy-phenyl) dilauryl aspartate
 N-(p-hydroxy-phenyl) cetyl isobutyl aspartate
 N-(p-hydroxy-phenyl) dibenzyl aspartate
 N-(p-hydroxy-phenyl) dicyclohexyl aspartate
 N-(p-hydroxy-phenyl) ditetrahydrofurfuryl aspartate

By carrying out the process of our invention as described in the above examples employing a diluent alcohol containing radicals dissimilar to the alcohol radicals of the maleic or fumaric diester, particularly advantageous gum inhibitor compositions may be obtained, as above pointed out, that are mixtures of two or more N-substituted aspartic acid diesters. Such mixtures, as above stated, may contain two different symmetrical diesters and may also contain the unsymmetrical diester; i. e., the diester containing in the same molecule one alcohol radical from the diluent alcohol and one alcohol radical from the maleic or fumaric diester. Examples of such gum inhibitor compositions are:

Mixed methyl and ethyl esters of N-(p-hydroxy-phenyl) aspartic acid
 Mixed methyl and isobutyl esters of N-(p-hydroxy-phenyl) aspartic acid
 Mixed ethyl and lauryl esters of N-(p-hydroxy-phenyl) aspartic acid
 Mixed ethyl and isobutyl esters of N-(p-hydroxy-phenyl) aspartic acid

Since certain changes in carrying out the above process, and certain modifications in the composition which embody the invention may be made without departing from its scope, it is intended that all matter contained in the above description shall be interpreted as illustrative and not in a limiting sense.

We claim:

1. In the production of an N-(p-hydroxy-aryl) aspartic acid diester by condensation of an unsaturated diester selected from the group consisting of maleic and fumaric diesters with a mononuclear aminophenol, the step that comprises bringing about such condensation by interaction between the unsaturated diester and the mononuclear aminophenol at a temperature of at least room temperature but under 150° C., in a liquid reaction medium containing as active ingredient at least 5% of a 1-5 carbon alkanol that is soluble at 25° C. in water to the extent of at least 0.5% by weight.

2. In the production of an N-(hydroxy-aryl) aspartic acid diester by condensation of an unsaturated diester selected from the group consisting of maleic and fumaric diesters with a mononuclear aminophenol, the step that comprises bringing about such condensation by interaction between the unsaturated diester and the mononuclear aminophenol, at a temperature of at least room temperature but under 100° C., in a liquid reaction medium containing as active ingredient at least 5% of a 1-5 carbon alkanol that is soluble at 25° C. in water to the extent of at least 0.5% by weight.

3. In the production of an N-(hydroxy-aryl) aspartic acid diester by condensation of an unsaturated diester selected from the group consisting of maleic and fumaric diesters with a hydroxy-aryl amine, the step that comprises bringing about such condensation by heating, at a temperature of at least room temperature but below about 150° C., a mixture of said diester, said amine, an aqueous solution of a 1-5 carbon alkanol that is soluble at 25° C. in water to the extent of at least 0.5% by weight said alkanol being present in amounts from one-half to five times the weight of said unsaturated diester, and about 0.4% to 4% by weight on the diester of an alkaline material substantially inert toward the reactants.

4. In the production of an N-(hydroxy-aryl) aspartic acid diester by condensation of an unsaturated diester selected from the group consisting of maleic and fumaric diesters with a mononuclear aminophenol, the step that comprises bringing about such condensation by heating, at a temperature of at least room temperature but below about 100° C., a mixture of said diester, said aminophenol, a 1-5 carbon alkanol that is soluble at 25° C. in water to the extent of at least 5% by weight said alkanol being present in amounts from one-half to five times the weight of said unsaturated diester, and about 0.4% to 4% by weight on the diester of an alkaline material substantially inert toward the reactants.

5. In the production of an antioxidant consisting of an N-(hydroxy-aryl) aspartic acid diester by condensation of an unsaturated diester selected from the group consisting of maleic and fumaric diesters with para-aminophenol, the step that comprises bringing about such condensation by interaction between the unsaturated diester and the para-aminophenol at a temperature in the range of about 60° to 90° C., in about 15% to 70% by weight of the reaction mixture of an aqueous solution of at least 25% concentration by weight of a 1-5 carbon alkanol containing about 0.4% to 4% by weight on the diester of an alkaline material substantially inert toward the reactants.

6. In the production of an antioxidant of the class of N-(hydroxy-aryl) aspartic acid diesters by condensation of an unsaturated diester selected from the group consisting of maleic and fumaric diesters with an aminophenol, the step that comprises bringing about such condensation by interaction between the unsaturated diester and the aminophenol at a temperature of at least room temperature but below about 150° C. in a liquid reaction medium containing as active ingredient at least 5% of a 1-5 carbon alkanol that is soluble at 25° C. in water to the extent of at least .5% by weight, in which alkanol the alcohol radical is different from the

alcohol radicals of the diester and by an alcoholysis reaction replaces to an extent of from 5% to 50% the original alcohol radicals of the diester with alcohol radicals derived from said alkanol.

7. A process as defined in claim 6 in which the unsaturated diester is a dialkyl fumarate.

8. A process as defined in claim 6 in which the unsaturated diester is a diaralkyl maleate.

9. In the production of an antioxidant comprising a mixture of N-(hydroxy-aryl) aspartic acid diesters by condensation of a dialkyl maleate in which the alkyl radicals contain no more than 5 carbon atoms, with para-aminophenol, the step that comprises bringing about such condensation by interaction between the dialkyl maleate and the para-aminophenol in 15-70% by weight of the reaction mixture of an aqueous solution of at least 25% concentration by weight of an alkanol in which the hydroxyl group is attached to an alkyl radical of not more than 5 carbon atoms, dissimilar to the alkyl radicals of said

10

unsaturated ester, at a temperature of at least room temperature but below about 100° C., whereby said unsaturated diester condenses with said para-aminophenol and at the same time an alcoholysis reaction takes place to substitute alkyl radicals of the alcohol to an extent of from 5% to 50% for the alkyl radicals of the diester.
